UNITED STATES PATENT OFFICE.

CARL A. MUEGGE, OF NEW BRUNSWICK, NEW JERSEY, ASSIGNOR OF ONE-HALF TO WILLIAM M. HOUSE, OF NEW YORK, N. Y.

SEWING-MACHINE.

SPECIFICATION forming part of Letters Patent No. 332,207, dated December 8, 1885.

Application filed April 19, 1884. Serial No. 128,512. (Model.)

To all whom it may concern:

Be it known that I, CARL A. MUEGGE, of New Brunswick, in the county of Middlesex and State of New Jersey, have invented certain new and useful Improvements in Sewing-Machines, of which the following is a specification.

This invention relates to that class of lock-stitch sewing-machines in which the lower thread is supplied from a bobbin placed within a horizontally-rotating cup-shaped bobbin-carrier having a hook for carrying the loops of needle-thread around the bobbin and its thread.

15 In the accompanying drawings, Figure 1 represents a side elevation of my improved sewing-machine; Fig. 1^a, a detail plan of the take-up. Fig. 2 is a bottom view of the machine; Fig. 3, an end elevation of the same. 20 Figs. 4, 5, and 6 are respectively a vertical central section on line *x* *x*, Fig. 2, a top view, and a side view of the horizontally-rotating bobbin-carrier and hook, drawn on a larger scale. Figs. 7 and 8 are a vertical central 25 section and a side view of the bobbin-case, and Fig. 9 is a detail side view of the needle-guard of the throat-plate. Fig. 10 is a side elevation, partly in section; and Fig. 11 is a section on the line 11 11 of Fig. 10, looking toward the 30 fly-wheel.

Similar letters of reference indicate corresponding parts.

Referring to the drawings, A represents the vertically-reciprocating needle-bar, which is operated, in the usual manner, by the main driving-shaft, supported in the hollow main arm C of the sewing-machine. On the main arm C are arranged the usual tension devices for the needle-thread and an oscillating take-up, D, which, instead of having one eye, is provided with three or more eyes, which work in connection with a fixed thread-guide, D', having one more eye than the movable take-up, as shown in Figs. 1, 1^a, and 3. The oscillating take-up D and thread-guide D' supply readily the required length of thread necessary for the proper working of the machine. The lower thread is supplied from a bobbin, F, which is placed bodily into a cup-shaped carrier, E, that is applied to the enlarged head or disk E' of a vertical shaft, E². This shaft turns in bearings E³, Fig. 4, below the table of the machine, and receives rotary motion

from a fulcrumed connecting-rod, E⁴, and suitable transmitting-gearing, n n', from the driving-shaft in the main arm C. The vertical shaft E² has a crank, e, at its lower end, which is connected by a pivot-link, e', to one end of the connecting-rod E⁴, while the opposite end of the same is connected to a crank, e², at the lower end of a vertical shaft, e³, that receives rotary motion by the usual bevel-gear transmission from the driving-shaft in the main arm of the machine. The fulcrum e' of the connecting-rod E⁴ is located on a horizontal lever, e⁵, pivoted on a fixed vertical rod, e⁶, as shown in Figs. 1 and 2. The bevel-gear n on the main shaft has double the number of teeth of the bevel-gear n on the vertical shaft e³, and the carrier E is thus caused to rotate twice while the needle makes one up-and-down stroke. The object of this double rotation of the rotary hook or bobbin-carrier is to enable the latter to loop the needle-thread quickly around the bobbin-thread, and still leave sufficient time before the needle again descends to enable the take-up to tighten and complete the stitch.

In place of imparting a continuous rotary motion to the bobbin-carrier a rotary reciprocating motion may be given to the same, by which the stitch is formed in the same manner, provided the hook is oscillated twice for each up-and-down stroke of the needle. The cup-shaped carrier E is secured by fastening-screws f to a segmental cheek, f', at one side of the disk-shaped head E', so that a nearly ring-shaped space, f², is formed between the carrier E and the head E', said cheek being situated in a horizontal plane low enough to give sufficient play to the carrier to turn horizontally around the needle without interfering with the up-and-down motion of the same. The carrier E is provided at one side with a curved recess, f³, and with a horizontally-projecting hook, g, that begins at the inwardly-pointed portion f⁴ of the recess f³. The curved recess f³ extends downwardly below the top of the disk-shaped head E', in which the bobbin-case rests, (see Fig. 6,) so that as the carrier rotates the loop of needle-thread caught by the hook g will be forced around under the bobbin-case resting in said head or disk. The hook g has an abutment, g', at some distance from the tapering end of the hook, back of which it tapers off again toward the carrier, as

shown clearly in Fig. 5. The needle passes through the hole of the throat-plate F' , and is guided along a downwardly-extending needle-guard, F^2 , of semicircular cross-section, 5 which has a notch, h , at one side of its lower end, as shown in Fig. 9. The notch h of the needle-guard F^2 serves for the purpose of retaining the needle-thread while the loop is formed by the horizontally-rotating hook g . 10 The bobbin-thread is supplied either directly from a wooden or other bobbin, or it may be placed in a metallic bobbin-case, G . (Shown in Figs. 7 and 8.) This is made of cylindrical shape, somewhat larger than the 15 bobbin, and provided with one or more tension-holes for the bobbin-thread, and with two exterior heels, i i' , of which the heel i at the middle part of the case rests against the needle-guard F^2 and retains the bobbin-case 20 in position, thereby preventing it from turning on its axis in the carrier E , while the heel i' at the lower part of the case takes up and holds the needle-thread for the formation of the loop by the hook g . The heels i i' also 25 prevent the bobbin-case from turning on its axis on the carrier E , as above described. I prefer to use a metallic bobbin-case, G , whenever a very accurate tension is desired to be imparted to the lower thread, while for ordinary 30 sewing the wooden bobbin without the bobbin-case will be sufficient. In using the bobbin without the case a certain degree of tension is imparted to the bobbin-thread, as the unwinding of the same takes place in opposite direction to that of the horizontally-rotating carrier, the bobbin being so placed within the carrier that as the thread unwinds from it while being taken up it will turn in a direction the reverse of that of the rotating carrier. 35

40 The feed-plate H rests upon the carrier H' , which is supported upon a fork-shaped oscillating lever, H^2 , the front end of which is drawn in a downward direction by a spiral spring, l , guided along fixed pins l' , and cushioned by 45 interposed spiral springs l'' , as shown clearly in Fig. 3. The oscillating feed-lever H^2 is fulcrumed at its middle portion to a centrally-pivoted cross-piece, l^3 , and acted upon at its opposite end by a vertically-reciprocating 50 tension-rod l^4 , operated, in the usual manner, by an eccentric, m , on the main driving-shaft, and by a laterally-oscillating crank, l^5 , that engages a transverse hole in the pin l' , which oscillates in a horizontal longitudinal recess 55 of the lever H^2 , as shown in Figs. 2, 10, and 11, and is operated by an arm, l^6 , which is actuated by the cam m' on the main driving-shaft. The cams m and m' are separated by the disk m^2 , as shown in Figs. 10 and 11. The piece l^5 60 has its pivot in the block p , which is vertically adjusted through its frame p' , to which it is pivoted by means of the screw p^2 . An up-and-down motion and a laterally-oscillating motion are thereby imparted to the feed by 65 the usual well-known means, whereby a regular forward feed is imparted to the fabric. The feed-plate and its actuating mechanism

are so arranged that they do not interfere with the bobbin-carrier and its actuating mechanism.

Having thus described my invention, I claim as new and desire to secure by Letters Patent—

1. The combination of a vertically-reciprocating needle, a throat-plate having a downwardly-extending needle-guard, a horizontally-rotating bobbin-carrier having a loop-forming hook, a bobbin-case having heels or projections adapted to engage said needle-guard, and means for imparting rotary motion to the carrier, substantially as set forth. 75

2. The combination of a vertically-reciprocating needle, a throat-plate having a downwardly-extending needle-guard, a cylindrical bobbin-carrier having a curved recess and an exterior loop-forming hook, and means whereby the bobbin-carrier is rotated twice for each up-and-down stroke of the needle, substantially as specified. 85

3. The combination of a horizontally-rotating bobbin-carrier provided with a curved downwardly-extending recess, as f^3 , extending below the top of the head or disk of the carrier, and an exterior horizontal hook, a vertical shaft having a disk-shaped head connected to said carrier, and mechanism for imparting rotary motion to said shaft, substantially as set forth. 95

4. The combination of a vertically-reciprocating needle, a throat-plate having a semicircular needle-guard notched at the lower end, a bobbin-carrier having a curved recess and an exterior hook, a vertical shaft having a disk-shaped head connected to the bobbin-carrier, and means whereby rotary motion is imparted to the carrier-shaft, substantially as described. 100

5. The combination of a vertically-reciprocating needle, a throat-plate having a downwardly-extending needle-guard, a horizontally-rotating bobbin-carrier having a curved recess and an exterior horizontal hook, a vertical shaft having a disk-shaped head, a bobbin-case resting on the disk-shaped head and having exterior heels for engaging said guard, and means whereby rotary motion is imparted to the carrier-shaft, substantially as set forth. 110

6. The combination of a vertically-reciprocating needle, a throat-plate having a downwardly-extending needle-guard notched at the lower end, a bobbin-carrier having a curved recess and exterior loop-forming hook, a vertical shaft having a disk-shaped head, means to connect the bobbin-carrier to said head, so as to leave a ring-shaped space between it and the carrier, and means whereby rotary motion is imparted to the carrier-shaft, substantially as set forth. 120

In testimony that I claim the foregoing as my invention I have signed my name in presence of two subscribing witnesses.
